UNITED STATES PATENT OFFICE.

FREDERICK S. STRONG, OF EAST BRIDGEWATER, MASSACHUSETTS, ASSIGNOR
TO THE CARVER COTTON GIN COMPANY, OF SAME PLACE.

SAND-PAPER ROLL.

SPECIFICATION forming part of Letters Patent No. 325,708, dated September 8, 1885.

Application filed June 23, 1884. (No model.)

To all whom it may concern:

Be it known that I, FREDERICK S. STRONG, of East Bridgewater, in the county of Plymouth and State of Massachusetts, have invented a new and useful Improvement in Sand-Paper Rolls, of which the following, taken in connection with the accompanying drawings, is a specification.

The object of my invention is to adapt to 10 the paper-holding roll a headed drag-pin, which, passing through the overlapped ends of the sand-paper, connects them together. This drag-pin, penetrating through the shell of the roller into the interior, is provided with 15 shoulders, with which grasping-jaws engage, these grasping-jaws being connected respectively to the ends of a yoke-spring, said spring being actuated by an eccentric which can be turned by a key from the outside. I attain 20 this object by the mechanism illustrated in the accompanying drawings, in which—

Figure 1 is a section through the center at right angles to the axis, showing my device as it appears when ready for use. Fig. 2 is a 25 similar section of the same, showing the paper overlapped and the dragging-pin pushed through ready to be grasped by the jaws, which serve to draw it firmly into the place indicated in Fig. 1. Fig. 3 is a vertical section taken on the line of the axis.

In the drawings a metallic case, A C D, is represented, the part A having a hub, B, attached to it, D being a ring-disk fastened to the part A by means of screw-bolts located at 35 E E E E, Figs. 1 and 2. This case A C D is covered with a suitable thickness of felt or some such yielding material, C. The sand-paper P is placed around the outside, the ends overlapping, as shown at p. Through these 40 overlapping ends I push the drag-pin H. The drag-pin H is provided with a head which has sufficient under surface to firmly hold the sand-paper. The pin H is pointed, as shown at h, so that it may readily penetrate the paper, and is provided with shoulders L L, Figs. 45 1 and 2.

S, Figs. 1 and 2, is a yoke-spring having jaws S' S² attached to its ends, these jaws being so formed, as shown in Figs. 1 and 2, that when they are drawn down between the fixed 50 buttresses K K they will approach each other and grasp the pin H and drag it down with them to the position shown in Fig. 1. Motion is imparted to the yoke-spring S and the jaws L L by means of the crank-disk N. This 55 crank-disk N has a crank-pin, N², which passes through a projection, S³, on the spring S, so that when the crank-disk N is turned the spring S and its parts will move up or down, as the case may be. A', Figs. 1 and 2, is a 60 buttress attached to the case A, and serves to limit the motion of the eccentric N so that it can only be turned slightly past its center—that is, enough to hold it from turning back. This eccentric N is provided with a square 65 socket, as shown at N', Fig. 3, for the purpose of receiving a key for operating it. This yoke spring S is very much extended at its lower end, so as to form almost a circle, as indicated in Figs. 1 and 2. This shape of the 70 spring allows it as a whole to elongate itself when subjected to great strain, so it will accommodate itself to a great extent to different thicknesses of felting.

I claim as my invention—

In a sand-paper roll, the combination of the 75 casing A C D, the buttresses K K, and stop A' with the crank-disk N, spring S, having jaws S' S², and the drag-pin H, whereby a yielding tensile strain is brought to bear on the covering of the wheel, all substantially as described, and for the purpose set forth.

In testimony whereof I have signed my name to this specification, in the presence of two subscribing witnesses, on this 20th day of June, 85 A. D. 1884.

FREDERICK S. STRONG.

Witnesses:

FRANK G. PARKER,
CHAS. SPAULDING.
